(57) **CLAIM**

The ornamental design for a compact brush, as shown and described.

DESCRIPTION

FIG. 1 is a top perspective view of a first embodiment of a compact brush;

FIG. 2 is a front view of the compact brush shown in FIG. 1;

FIG. 3 is a back view of the compact brush shown in FIG. 1;

FIG. 4 is a right side view of the compact brush shown in FIG. 1;

FIG. 5 is a left side view of the compact brush shown in FIG. 1;

FIG. 6 is a top view of the compact brush shown in FIG. 1;

FIG. 7 is a bottom view of the compact brush shown in FIG. 1;

FIG. 8 is a bottom perspective view of the compact brush shown in FIG. 1;

FIG. 9 is a top perspective view of a second embodiment of a compact brush;

FIG. 10 is a front view of the compact brush shown in FIG. 9;

FIG. 11 is a back view of the compact brush shown in FIG. 9;

FIG. 12 is a right side view of the compact brush shown in FIG. 9;

FIG. 13 is a left side view of the compact brush shown in FIG. 9;

FIG. 14 is a top view of the compact brush shown in FIG. 9;

FIG. 15 is a bottom view of the compact brush shown in FIG. 9; and,

FIG. 16 is a bottom perspective view of the compact brush shown in FIG. 9.

The dashed lines in FIGS. 1-2, 4-5, 7, 9-16, and 25-32 are included for the purpose of illustrating portions of the compact brush that form no part of the claimed design.

1 Claim, 24 Drawing Sheets

CERTIFICATE OF CORRECTION

PATENT NO. : D910,585 S
APPLICATION NO. : 29/656832
DATED : February 16, 2021
INVENTOR(S) : Jenny DeMarco Staab

Page 1 of 1

It is certified that error appears in the above-identified patent and that said Letters Patent is hereby corrected as shown below:

On the Title Page

Delete "24 Drawing Sheets" and insert -- 12 Drawing Sheets --.

(57) DESCRIPTION, Line 32:

Delete "FIGS. 1-2, 4-5, 7, 9-16, and 25-32" and replace with -- FIGS. 1-2, 4-5, and 7 --.

In the Drawings

Delete FIGS. 17-32 (Drawing Sheets 13-24).

Signed and Sealed this
Twenty-ninth Day of June, 2021

Drew Hirshfeld
